DISPENSING NOZZLE FOR A PRESSURIZED CONTAINER

Ernst Claes Kare Allvarsson Lonegren, 2 Ravstigen,
Saltsjö Duvnäs, Sweden

Filed Dec. 11, 1974, Ser. No. 531,498

Claims priority, application Sweden June 17, 1974

Term of patent 14 years

Int. Cl. D9—07

U.S. Cl. D9—258

FIG. 1

FIG. 2

FIG. 3

FIG. 4

FIG. 5

FIG. 1 is a top perspective view of a dispensing nozzle for a pressurized container showing my new design with a container being shown in broken lines for illustrative purposes only;

FIG. 2 is a bottom perspective view on an enlarged scale;

FIG. 3 is a side elevational view;

FIG. 4 is a top plan view; and

FIG. 5 is a bottom plan view.

I claim:

The ornamental design for a dispensing nozzle for a pressurized container, as shown and described.
